M. H. MILMAN.

WINDOW SCREEN.

APPLICATION FILED MAR. 10, 1917.

1,265,477.

Patented May 7, 1918.

Inventor
Maurice H. Milman,
By Robert M. McCracken
Attorney

UNITED STATES PATENT OFFICE.

MAURICE H. MILMAN, OF BROOKLYN, NEW YORK, ASSIGNOR OF ONE-HALF TO ELI HELLER, OF WILKES-BARRE, PENNSYLVANIA.

WINDOW-SCREEN.

1,265,477.

Specification of Letters Patent.

Patented May 7, 1918.

Application filed March 10, 1917. Serial No. 153,921.

To all whom it may concern:

Be it known that I, MAURICE H. MILMAN, a citizen of the United States, residing at Brooklyn, in the county of Kings and State 5 of New York, have invented certain new and useful Improvements in Window-Screens, of which the following is a specification.

The present invention relates to screens for windows of houses and the like and consists in the combinations and arrangements 10 of elements hereinafter described and particularly set forth in the accompanying claim.

The invention has for its purpose to provide a window structure having a screen 15 slidably concealed therein and adapted to be connected to the window sash and brought into position for screening the window opening when the window is raised.

20 The invention has for its further purpose to provide a window structure of this character in which the screen is effectively concealed from view when not in position and wherein means are provided for engaging 25 the screen to position the same or release the screen when it is not to be used, all in a simple and easily performed manner.

The invention is disclosed by way of illustration in the accompanying drawings, 30 wherein—

Figure 1 is a front elevational view, partly broken away, showing the application of the device.

Fig. 2 is an enlarged detail view showing 35 the means for raising or releasing the screen, and

Fig. 3 is a transverse sectional view taken on the line 3—3 of Fig. 1.

Referring to the construction in further 40 detail and wherein like reference characters designate corresponding parts in the different views shown, 4 designates the window frame having slidably mounted therein the usual upper and lower sashes 5 and 6, and 45 the wall structure 7 beneath said frame is formed with a chamber or recess 8 to receive and conceal the screen 9, having a suitable form of rigid frame 10, as shown.

The screen chamber 8 is located immedi- 50 ately beneath and in the plane of the sliding

sash 6, to the end that said screen may be lifted to screen the window opening when the sash 6 is raised. By this arrangement the window screen is placed into position without requiring the additional and troublesome labor which is now necessary, and there is the further advantage that the window is not left open for any period of time at all for the placing of the screen into position.

55 The means for lifting the screen consists of a pair of latches 11 that are pivotally mounted within an enlargement or chamber 12 that is formed in the lower edge of the sash frame piece 13 (see Figs. 2 and 3). A 60 groove or channel way 14 is also formed in the sash frame 13, and extends for the full length of said piece to receive the upper frame portion 15 of the screen. Said frame portion consists of a pair of metal strips 65 suitably connected to bind the edge of the screen, and at its middle portion both strips are separated to receive the pair of pins 16 that are adapted to be engaged by the spring-pressed latches 9, for raising the sash 70 into position.

75 The two latches 11 are provided with a pair of hand-engaging members 18 working in slots 17 for the purpose of disengaging the latches from the pins 16 when it is not 80 desired to move the screen into position i. e. when weather conditions do not necessitate the use of a window screen.

85 It is obvious that those skilled in the art may vary the details of construction and arrangement of parts without departing from the spirit of my invention, and therefore I do not wish to be limited to such features except as may be required by the claim.

90 Having thus described my invention, what I claim and desire to secure by Letters Patent is:

95 The herein described improvement in window screens consisting of the upper rail of the screen formed with a recess, a pair of transverse pins arranged in said recess, the meeting edge of the sash formed with a recess in line with the recess of the screen rail, a pair of spring-actuated latches

mounted in the recess of the sash and adapted to engage the pair of pins, handles for operating said latches, said lower rail of the sash being formed with a groove to fit 5 snugly over the upper rail of the screen to make a close joint between the sash and screen.

In testimony whereof I affix my signature in the presence of two witnesses.

MAURICE H. MILMAN.
